[57] CLAIM

The ornamental design for a digital multi-meter, as shown and described.

DESCRIPTION

FIG. 1 is a front view of a digital multi-meter showing our new design;

FIG. 2 is a right side view thereof;

FIG. 3 is a rear view thereof;

FIG. 4 is a left side view thereof;

FIG. 5 is a top plan view thereof;

FIG. 6 is a bottom plan view thereof;

FIG. 7 is a magnified front view of the digital multi-meter, showing a state that the digital multi-meter is turned on;

FIG. 8 shows a front view of the digital multi-meter, showing schematics when the digital multi-meter is used;

FIG. 9 shows a front view of the digital multi-meter, showing schematics when the digital multi-meter is used;

FIG. 10 shows a front view of the digital multi-meter, showing schematics when the digital multi-meter is used;

FIG. 11 shows a front view of the digital multi-meter, showing schematics when the digital multi-meter is used;

FIG. 12 shows a front view of the digital multi-meter, showing schematics when the digital multi-meter is used;

FIG. 13 shows a front view of the digital multi-meter, showing schematics when the digital multi-meter is used;

FIG. 14 shows a front view of the digital multi-meter, showing schematics when the digital multi-meter is used;

FIG. 15 shows a front view of the digital multi-meter, showing schematics when the digital multi-meter is used; and,

FIG. 16 is a perspective view of the digital multi-meter.
